Wagner Protective Wedge [Oct. 30, 2019] found online [Oct. 30, 2019]—<https://detail.en.china.cn/provide/p156958274.html>.*Primary Examiner* — John A Voytek*(74) Attorney, Agent, or Firm* — BakerHostetler(57) **CLAIM**

The ornamental design for a powder spray gun component, as shown and described.

DESCRIPTION

FIG. 1 is a top perspective view of a powder spray gun component;

FIG. 2 is a top end view thereof;

FIG. 3 is a bottom end view thereof;

FIG. 4 is a left side view thereof;

FIG. 5 is a right side view thereof;

FIG. 6 is a rear end view thereof; and,

FIG. 7 is a front end view thereof.

The broken lines in the drawings are depicting unclaimed portions of the powder spray gun component and form no part of the claim.

1 Claim, 4 Drawing Sheets(56)
